Specification for Design.

Patented May 10, 1921.

Application filed September 22, 1919. Serial No. 325,558. Term of patent 14 years.

To all whom it may concern:

Be it known that I, EARNEST E. MULLVAIN, a citizen of the United States, and resident of the city and county of San Francisco, and State of California, have invented a new, original, and ornamental Design for an Automobile Direction-Signal, of which the following is a specification, reference being had to the accompanying drawing, forming a part thereof.

In the drawing:

Figure 1 is a front elevation of the direction signal,

Fig. 2 is an end view, and
Fig. 3 a perspective view.

What I claim is:—

The new and ornamental design for an automobile signal substantially as shown.

In testimony whereof, I have hereunto set my hand this 2nd day of September 1919, in the presence of the two subscribed witnesses.

EARNEST E. MULLVAIN.
